UNITED STATES PATENT OFFICE.

ALDEI LANDRY, OF CENTRAL FALLS, RHODE ISLAND, ASSIGNOR TO HEMPHILL COMPANY, OF CENTRAL FALLS, RHODE ISLAND, A CORPORATION OF MASSACHUSETTS.

SPLIT-WORK KNITTING MACHINE.

1,415,583.

Specification of Letters Patent. Patented May 9, 1922.

Application filed February 5, 1919. Serial No. 275,228.

To all whom it may concern:

Be it known that I, ALDEI LANDRY, a citizen of the United States, residing at Central Falls, in the county of Providence, State of Rhode Island, have invented a certain new and useful Improvement in Split-Work Knitting Machines, of which the following is a specification, reference being had therein to the accompanying drawings.

10 The invention has relation to circular knitting machines such as are constructed to produce webs comprising a portion knit in complete courses of the same yarn or yarns upon the full series of needles, succeeded by 15 a portion composed of narrow longitudinal sections knit respectively of different yarns upon different laterally-adjacent sub-series of the needles. Machines of this class adapted for the production of what are 20 termed split-foot stockings are called split-foot knitting machines. A split-foot stocking has the top of the foot thereof composed of a longitudinal section knit in short courses of one yarn upon one sub-series of 25 needles, and the bottom of the foot composed of a similar section similarly knit of a different yarn or yarns upon a second sub-series of needles, with the said sections united to each other along the sides of the 30 foot by the interknitting of the marginal loops or stitches of one section with those of the other so as to form so-called seams or sutures. Sometimes stockings are knit with similar split-work high-spliced ankle 35 portions. In some classes of work, the narrow longitudinal sections are produced as strips which are left unconnected with each other along their margins.

The invention comprises improvements 40 which obviate certain important drawbacks and disadvantages of split-foot knitting machines and other like machines heretofore known in the art. It includes various novel and improved features and combinations in 45 connection with the various cams and pickers and the supporting means for such parts, and the means for operatively controlling the cams, pickers, supports, etc.; and in connection with the yarn-guide for 50 the auxiliary feed.

The invention includes also an improved construction of the sinkers or web-holders and of their actuating means whereby during the knitting of the full courses the sinkers or web-holders shall be caused to dwell

in their wale-engaged position in passing the auxiliary feed, but during split-foot knitting they shall be moved radially at such feed.

The accompanying drawings represent an 60 illustrative embodiment of the features of the invention in a circular split-foot stocking knitting machine of the well-known Banner type.

In the said drawings,—

Fig. 1 is a front elevation of sufficient of the said machine, with the embodied improvements, to illustrate the nature and application of the invention, a small portion of the block of the main knitting-cam system 70 being broken away.

Fig. 1^a is a detail view in plan showing more particularly the means hereinafter described for taking up side-play.

Fig. 2 is a side elevation of the parts 75 which are shown in Fig. 1.

Fig. 3 is a rear elevation thereof.

Fig. 4 is a view showing a needle separately.

Figs. 5, 6, and 7, are views showing the 80 three different forms of jacks that are employed in the said machine.

Figs. 8 and 9 are views showing the different forms of sinkers that are employed therein.

Fig. 10 is a bottom view of the sinker-cam ring and certain parts employed for moving the two-stepped cam at the auxiliary feed into its different positions, with lever 50 in cross-section on line 10—10, Fig. 1.

Fig. 10^a is a view in cross-section on line 10^a—10^a, Fig. 10, of the movable sinker-cam at the auxiliary feed, showing such cam right side up.

Fig. 11 shows pattern-controlling devices 95 for the movable block of the widening pickers and the movable block of the auxiliary cams.

The organization in general of the machine that is partly shown in the drawings 100 is substantially on the order of that indicated in U. S. Letters Patent to J. D. Hemphill, No. 933,443, granted Sept. 7, 1909, for improvement in circular automatic stocking knitting machines. The so-called split-foot 105 organization, apart from the features of improvement comprised in the present invention, is substantially on the order of that indicated in U. S. Letters Patent to George P. Bosworth, No. 1,154,169, granted Sept. 21, 110

1915 for improvement in automatic circular knitting machines for producing split-foot hosiery. The drawings show only such parts as are required to be shown in order to illustrate the features of the invention and render clear the relations, etc., of the parts that are involved more immediately in the invention.

Certain of the parts in the drawings corresponding with those of said Hemphill Patent No. 933,443 are designated herein by the same reference characters as in such patent; namely, the main frame a , the table or bed a^2 thereof, the rotatable needle-cylinder N , the sinker-bed n^6 , the sinker cam-ring G , the latch-ring C , and the yarn-guides d^7 of the main feed. Also, the non-rotatable cam-carrying plate H , and the cam-block D provided with the main knitting cams and with the narrowing pickers R , R . Also, the widening pickers T , T , the mounting of said pickers upon a radially-movable block being novel with the present invention, however. Also, the vertically-guided slide-bar g^3 with the top of which the cam-carrying plate H is connected, said slide-bar having connected with its lower end the holder g^2 for the pins or so-called "pawls" g' that are engaged by pattern-cams of the pattern-wheel g (on the pattern-barrel shaft) for controlling the height and vertical movements of the cam-carrier H and cam-block D and thereby determining and varying the length of the stitches. Also, the clutch-lever b' controlled by the pattern-barrel and itself controlling the clutch-hub b on the actuating shaft for the needle-cylinder so as to place the said clutch-hub in engagement either with the continuously rotating gear i' for continuous round and round knitting, or with the oscillating gear i'' for reciprocating knitting.

The elements of the needle-actuating cam-systems are closely similar to those of Patent No. 1,154,169, with the differences in arrangement, etc., which are characteristic of the present invention, and which are explained in the following portions of the specification. Thus the wing cams of the main cam-block D are indicated at v^3 , Fig. 1, and v^4 , Fig. 3, and the top or guard cam at v^5 . The auxiliary cam-block, located at the opposite side of the machine from the main cam-block D , is indicated at B' . Its side or wing-cams are indicated at u^3 , u^4 , and its right and left upper guard cams are indicated at c' , c^2 , the plate or bar by which the said guard cams are supported upon the main part of the said block B' being indicated at c . At E , Fig. 3, is the pivoted switch-cam at the back of the machine which is associated with cams c^2 and u^3 , its depressing spring being indicated at e^x , Figs. 2 and 3. M and M' , Fig. 1, are race-cams, so-called, at the front of the machine, and

M^x , Fig. 3 is a similar cam at the back of the machine. At d^x is the yarn-guide of the auxiliary feed, delivering yarn to be knit by the needles which are actuated to knit by the cams of the auxiliary cam-block B' .

As is well-known to those versed in the art, a split-foot stocking knitting machine is constructed with two sets of knitting cams and with two yarn feeds conjoined therewith, usually one of such sets and its yarn feed being in operation only during split-work knitting. Also, with pickers for narrowing and widening to form heel and toe pouches and for operating the seam or suture needles for the production of the seams or sutures, and with pattern-connections by means of which the working of the parts is controlled. Heretofore, the two sets of knitting cams, and all the pickers, have been arranged at substantially one level in a machine, and have been mounted in connection with one supporting plate. From this results a very crowded condition because of too many parts being assembled close together side by side at substantially the same level in connection with a common support, and there further results an inconvenient lack of accessibility of the needle-cylinder and needles and the parts themselves. Moreover, the auxiliary knitting parts are too small because of the necessity of confining the auxiliary set of knitting cams, etc., within a comparatively narrow portion of the circumference of the needle-cylinder. There also is a lack of capacity for independent adjustment of the two sets of knitting cams by which to enable the closeness or looseness of the knitting of one longitudinal section of the "split" part of the stocking to be varied with respect to that of the other of the said sections, as, for instance, in order to compensate for differences between the yarns employed in knitting the respective sections, or in order to secure a desired difference in character or appearance between said sections. Because of this lack of capacity for independent adjustment it is practically impossible to secure uniformity of appearance between the two opposite sections of knitted web, viz. The upper and lower portions of the foot for instance, when such uniformity is desired. Another cause of lack of uniformity in such appearance in the case of machines heretofore in use is the fact that the needles used therein have butts of three different lengths, short, medium, and long. Those employed in knitting one of the said sections of knitted web (the heel, foot-bottom, and toe) have short butts, and the corresponding set of knitting cams (the main set) engage with such butts close to the surface of the needle-cylinder. Those employed as seam or suture needles have butts of medium length. Those employed in knitting the other of said sections (the in-

- step and top of the foot) have long butts, and the instep raising cam and pivoted switch cam E are arranged to engage with said long butts at a distance from said surface sufficient to enable such cams to clear the medium butts. The action in knitting of knitting cams located at a fairly considerable distance outward from the surface of the needle-cylinder upon the long needle-butts tends to tip the hooked ends of the long-butts radially outward. This operates to render the length of the stitches produced by such needles greater than that of those produced by the short-butts needles.
- 15 In addition, this tipping of the long-butts needles tends to occasion breakage of the needle-butts, in consequence of causing the lower ends of such needles to bind and cramp in the needle-grooves of the needle-cylinder. Furthermore, by the carrying of the needle-hooks outward toward or against the surface of the latch-ring, the proper taking of the yarn by such hooks is interfered with.
- 20 25 I do away with the drawbacks and disadvantages which have just been recited by the following improvements:
- I dispose the auxiliary cams and pickers which are brought into play for split-work knitting at a different level in the machine from that of the cams and pickers which are employed for round and round knitting and heel and toe work, and, as shown clearly in Figs. 1, 2, and 3, mount the respective sets of cams and pickers, thus disposed at different levels in the machine, upon different supports. In the drawings, the main cam-block D, located at one side of the machine and provided with the main knitting cams and the narrowing pickers R, R, and a block 1, located at the opposite side of the machine and carrying the widening pickers T, T, are mounted at substantially one level in the machine, upon one support, herein the cam-carrying plate H. The auxiliary cam-block B', with its auxiliary cams and the seam or suture pickers u, u', is disposed at another level below the first, upon a second support, herein the cam-carrying plate 2. The said cam-carrying plate H is supported higher above the bed-plate a² than in the prior machines, with a space between plate H and bed-plate a² sufficient to accommodate the auxiliary cams and seam or suture-needle pickers u, u', and the said supplemental cam-carrying plate 2.
- In general terms, by the location of the auxiliary cams and pickers at a different level from the others, I obviate the crowded condition that is found in prior machines; render the needle-cylinder, needles, and various other parts, more accessible; enable the respective parts to occupy more space circumferentially of the needle-cylinder, and enable the parts to be made of larger and better proportions and to be spaced more conveniently and advantageously. The greater openness of the parts which surround the needle-cylinder, and consequent increased accessibility of the portions of the needle-cylinder which are adjacent and between the said parts, and of the knitting parts themselves, are of importance because thereby adjustments are facilitated, as well as the removal and replacement of broken or damaged needles and other parts. Furthermore, it is made possible to provide for adjustment of the seam or suture pickers u, u', to suit the path of the butts of the seam or suture needles, by means of adjustment-screws u^x, u^x, Figs. 1, 2, and 3, mounted upon block B' and arranged to act against outwardly-extending tails formed upon the hub-portions of the said pickers. Similar adjusting screws r^x, r^x, are shown combined with the narrowing pickers R, R, of the main cam-block D.
- The support 2 for the auxiliary cams, etc., and the support H for the main cams, are raised and lowered in unison in the working of the machine. Preferably this is provided for, as shown, by connecting the two supports with each other. This connection is effected in the illustrated embodiment of the invention by means of a bar 10 extending down from the supporting-plate 2 and fitted to a vertical recess in the upright portion 11 of an arm 12, the said arm forming a rearward extension of the holder g² for the pawls or pins g' that rest on the peripheral portions of the pattern wheel g, the holder and arm 12 being made fast to the bar g³ of the supporting-plate H by means of bolt g^x, Fig. 3. The bar 10 is confined in the said recess of the portion 11 by means of a cap-plate 13 that is held in place upon the face of such portion by means of screws 14, 14.
- I make provision for relative vertical adjustment of the supports H and 2 with respect to each other. Thereby I secure capacity for independent relative adjustment of the two sets of knitting cams with respect to each other, and remedy the deficiency of prior machines which interferes with varying the closeness or looseness of the knitting of the respective longitudinal sections of split work. In the illustrated embodiment, the lower end of the bar 10 rests upon the upper end of an adjusting or set-screw 10^a occupying a threaded hole that is tapped through the bottom wall of the recess in portion 11 of supporting-arm 12. By means of the said screw the height of the supporting-plate 2 and the auxiliary cams relative to the main supporting-plate H and the main cams may be adjusted to a nicety to secure the required degree of correspondence, (or difference) in the stitches of the opposite sections of the split work. For the purpose of clamping the bar 10 within the said recess, after vertical

adjustment has been effected, a clamping screw 15, Figs. 1 and 2, is combined with one side of the upright portion 11, a plug 16, Fig. 2, of brass, or other suitable material, 5 being interposed between the inner end of the said screw 15 and the edge of the bar 10 to avoid the formation of an indentation or burr in or upon such edge. By tightening up the screw 15 all lateral looseness and play 10 of the bar 10 within the recess of the part 11 is taken up, and accidental lifting of plate 2, as in consequence of strain, resulting from a bunch of yarn becoming engaged by the needles, while the latter are being drawn 15 down by the action of the auxiliary cams of block B', or otherwise, will be prevented.

By the adjustability of the two sets of cams relative to each other I am enabled to control the closeness or looseness of the knitting 20 of each of the two longitudinal sections of a "split" part of a stocking, so as to secure uniformity of appearance between the two portions thereof, or any desired difference in appearance.

25 By way of still further guarding against lateral movement of the supporting-plate 2 and parts carried thereby, a block 17, Fig. 1^a, Sheet 1, and Fig. 2, at the upper end of the bar 10 is located within a recess 18 in 30 the adjacent edge of the bed-plate α^2 of the machine, as shown in Figs. 1^a and 2, and wedge-shaped pieces 19, 19, Figs. 1, 1^a, and 2, are applied to the opposite sides of the said block 17, their inner portions being entered 35 between the said sides and the adjacent walls of the notch 18. These wedges 19, 19, are secured to the sides of the block by means of screws 20, 20, the wedges being slotted longitudinally at 21 to provide for longitudinal 40 adjustment of the wedges to take up lateral looseness and play of the bar within the recess.

To suit the disposition of the cams and pickers at two different heights or levels in 45 the machine, I provide in connection with the needles two sets of butts or heels, also arranged respectively at different levels, for engagement with the respective sets of cams. These butts or heels for convenience are provided upon jacks, Figs. 5, 6, and 7, which are engaged with the needles in usual manner. One of the jacks of the instep needles is shown at 3, Fig. 5; Fig. 6 shows one of the jacks, 4, of the needles used for knitting 50 heels and toes and foot-bottoms; Fig. 7 shows one of the jacks, 5, of the seam or suture needles. Inasmuch as all of the needles are actuated by the main cams for round and round knitting, all of the jacks, 55 60 3, 4, 5, are furnished with butts 3^a, 4^a, 5^a, at one height for engagement with such cams, the said butts 3^a, 4^a, and 5^a, constituting one of the said sets, which is a complete circular series. For the actuation of the instep needles and seam or suture needles by the aux- 65

iliary cams during reciprocating knitting for the production of split-work, the jacks 3 of the instep needles and the jacks 5 of the seam or suture needles are furnished respectively, with additional butts 3^b and 5^b, at a 70 second height. These additional butts collectively constitute a secondary series, which is the second of the said sets. The needles which knit the heel and toe, and bottom of the foot, as well as the back of a high-splice, 75 are not engaged by the auxiliary cams; their jacks, 4, have no secondary butts.

By reason of there being no butts of the heel and toe needles (apart from the seam or suture needles) in the secondary series 80 of butts or heels, I am enabled to give the auxiliary cams a working position much closer to the surface of the needle-cylinder than heretofore. In fact, I may and usually do allow their faces to make contact with the 85 said surface when the said working position is assumed. This permits making the butts, 5^b, of the seam or suture needles short as in Fig. 7, and the butts, 3^b, of the instep needles of medium length, instead of making 90 the said butts medium and long as heretofore. This, also, permits the instep-raising cam i^3 and pivoted switch-cam E to have working positions closer to the surface of the needle-cylinder than heretofore, namely 95 only far enough outward from said surface to clear safely the short butts of the seam or suture needles. Thereby I avoid the disadvantages of having butts of three lengths (short, medium, and long) as heretofore, 100 and of operating the instep needles by means of cams engaging at a considerable distance outward from the needle-cylinders with the outer portions of long butts upon such needles. 105

In order that the auxiliary cams may be caused to assume an idle position, retracted outward clear of the secondary butts, as during round and round knitting or heel and toe knitting, or an inward working position 110 suitable for engagement with said butts, as during the knitting of split-work, the block B' is mounted on its supporting-plate 2 with capacity to slide thereon radially with reference to the needle-cylinder N. It is shown 115 as held down upon the plate 2 by means of bent pieces 23 which are attached by screws 23^a, 23^b, to the side edges of plate 2 and have their top portions bent inwardly over the side marginal portions of the block B', so 120 as to hold the latter down while at the same time permitting the radial movement. This is merely a convenient construction for the purpose.

The parts through which the position of 125 the block B' is controlled by the pattern-surface comprise a link 25, Figs. 2 and 3, a bell-crank 26, and a lever 27 acting by one arm thereof upon said bell-crank and connected by a rod 28 with a lever or finger 28^a, 130

Fig. 11, that is controlled by the portions 28^b of the pattern surface. By means of an elevated portion 28^b of the pattern surface acting through the said parts, the block B' 5 is moved outward, so as to withdraw the auxiliary cams and pickers out of working relations with the lower butts 3^b and 5^b, and so long as such a portion continues in engagement with the lever or finger 28^a the 10 said block B' is held in its outward or idle position. An expanding spiral spring 29, Fig. 1, confined between an upwardly projecting portion of the cam-block and a block 30 upon supporting-plate 2, pushes the block 15 B' inward toward the needle-cylinder when permitted by the pattern surface, and holds it in the inward position during the knitting of split-work.

The devices for controlling the auxiliary 20 cam-block B' which have just been described operate with positive action in moving the said cam-block outward, but operate to move it inward with yielding force. Herein resides one of the features of improvement. 25 By reason of moving the block inward with yielding force, no injury from strain will result in case the block should be prevented from moving all the way in by a broken piece of needle fallen in between 30 the block and the needle-cylinder, or by other cause. In prior machines the cam-block B' is moved inward positively. Hence, if a piece of needle, or other object, should fall in between the said block and the 35 needle-cylinder while such block occupies its outward position, as during the knitting of the leg of a stocking, or of a heel or toe, so as to prevent the block from moving the full distance inward, the parts concerned in 40 producing the inward movement would be strained and either bent or broken. If bent, adjustment would be necessary.

A modified arrangement of the instep cams i^3 , i^4 , is necessitated by the disposition 45 of the butts in two series at different heights, the said cams being arranged as shown best in Fig. 1 so that lower instep cam i^3 cooperates with butts of the lower or secondary series, by acting upwardly thereagainst, 50 while upper instep cam i^4 cooperates with butts of the upper series, by acting downwardly thereagainst. The two cams, i^3 , i^4 , are separated vertically more widely than heretofore upon their carrying-bar i^5 , shown 55 in dotted lines in Fig. 1. The said carrying-bar is mounted for the required vertical movement thereof in a guideway in a stand i^7 that is attached to the upper cam carrying-plate H. The actuating connections 60 through which bar i^5 and instep cams i^3 , i^4 , are moved upward and downward at the required times in the working of the machine comprise a bell-crank 5 which is pivoted at 6 upon the lower portion of said 65 stand, with one arm thereof slotted to re-

ceive a screw 5^a projecting from the bar i^5 , and a link 7 extending from the other arm of said bell-crank to the upper arm of clutch-lever b', the said link being engaged with said arm by means of a stud-screw 8 carried by the arm and working with lost-motion in a slot 9 in the link. When the clutch-lever is actuated to shift clutch-hub b into engagement with oscillating gear i^7 for reciprocating knitting, motion is transmitted 70 by means of the link and bell-crank to raise the cams i^3 , i^4 so that the cam i^3 may act against the lower butts of the instep needles to raise such needles out of working relations with the main knitting cams and into 75 the elevated position which they are required to occupy during reciprocating knitting; and when the clutch-lever is moved oppositely so as to shift clutch-hub b into engagement with the continuously-rotating 80 gear i^7 the cams i^3 , i^4 , are moved downward so that cam i^4 may act upon the said upper butts to depress the instep needles and carry such butts into position to be engaged by the main knitting cams for round and round 85 knitting.

The block 1 carrying the widening pickers T, T, is mounted upon the upper supporting-plate H with capacity for movement radially toward and from the needle-cylinder, 90 in order to place the said pickers in and out of working relations with the butts 4^a of the needles on which the heel, etc., are knit. During round and round knitting, and also during narrowing, the said block and pickers 95 occupy their outwardly retracted position. They are caused to occupy the outwardly-retracted position during the reciprocating knitting of split-work, because if at such time the widening pickers were left inward 100 trouble would result sometimes, as in the case of a misplaced needle. It is difficult to adjust the said pickers so as to avoid trouble of this kind. Sometimes a needle jumps as a result of contact with a narrowing picker, 110 which would involve undesired engagement with a widening picker if the latter were inward. The position of block 1 is determined by means of the pattern surface and connections comprising a lever 31 pivoted by screw 115 31^a, Fig. 2, on one edge of block B' and having its upwardly-extending arm engaged in a slot in a plate 32 that projects outward from the block 1, the said lever 31 being actuated by means of a lever 33 which is connected by means of a rod 34 with a lever or finger 34^a, Fig. 11, that is in direct engagement with the pattern surface. The pattern surface, acting through these connections, operates to move the block 1 outward into 120 its position shown in Figs. 1 and 3 and normally holds it in such outward position. An expanding spiral spring 35, Figs. 1 and 3, confined between the outer end of the block 1 and a fixed piece 36 upon the supporting- 125 130

plate H, operates to move the block inward when permitted to do so by the pattern surface, and holds the block in its inward position, with the pickers T, T, in working relations with the said butts 4^a during the widening operation in forming a heel or toe bulge or pouch.

The tapering gauge-plate k⁶ by which the elevated positions of the widening pickers 10 T, T, are controlled is mounted upon the block 1 in a manner providing for adjustment of the said gauge-plate inward and outward. The gauge-plate is affixed to the inner end of a carrier-block k^x occupying a 15 slot in the top of the block 1, said carrier-block being secured in place in the said slot by means of a screw k^z. The stem of said screw passes vertically through a longitudinal slot in the carrier-block, permitting the 20 carrier-block and gauge-plate to be set in or out as required, and fastened in place. A setting of the carrier-block and gauge-plate farther inward operates to lower the waiting positions of the engaging ends of the pickers 25 T, T. A setting of the same farther outward operates to permit said engaging ends to occupy higher waiting positions.

Stops are provided for the purpose of limiting the extent of the inward movement 30 of the blocks D and 1 so as to relieve the needle-cylinder from the inward pressure of the cams and pickers which are carried by the said blocks. The stop for limiting the inward movement of the block D consists in 35 a plate 351, Fig. 1, attached by a screw 35^x to the top of the supporting-plate H. Said plate extends under the outer portion of the block D, and has an upturned lug that engages with a shoulder that is formed at the 40 outer end of a recess in the under side of block D. This stop 35 is slotted longitudinally, at 35^y, to enable it to be adjusted in or out so as to vary the closeness of approach of the main knitting cams to the surface of 45 the needle-cylinder under the action of spring d^y and the engagement of the narrowing pickers with the needle-butts. The stop for limiting the inward movement of the block 1 is constituted by a screw 361 carried 50 by the downturned outer end of a plate 37 that is attached to block 1 and projects outward therefrom. The inner end of the said screw 361 is adapted to make contact with the adjacent edge of the supporting-plate H. 55 By adjustment of the said screw-stop the closeness of the approach of the block 1 and parts carried thereby to the cylinder may be regulated to a nicety, and thereby the engagement of the widening pickers with 60 the butts 4^a may be regulated.

The means for controlling the yarn-guide d^x of the auxiliary feed so that except during the knitting of split-work it shall occupy its non-feeding position, and so that it shall 65 assume the feeding position at the time of

beginning to knit split-work, comprises in the case of the machine shown in the drawings a lever 50 adapted to engage with the said yarn-guide. The said lever is pivoted at 50^x, Fig. 3, upon one edge of cam-carrying-plate H, and its lower arm is engaged by a plate 51 carried by auxiliary cam-block B'. The relations, etc., are such that while the said cam-block B' occupies its idle outward position it holds the lever 50 in a position in which through engagement with yarn-guide d^x it keeps the latter inward in an unraised idle and non-feeding position. Movement of cam-block B' inward into working position for beginning to knit split-work operates lever 50 to permit yarn-guide d^x to be moved by its spring d² downward and outward into feeding position, as shown.

As usual, except while split-work knitting is being performed, the sinker-projecting cam G², Fig. 10, adjacent the auxiliary feed remains in its inward non-working position, and hence ordinarily the sinkers are not moved radially as they and the needles with which they operate pass such feed. For split-work knitting the said cam is moved by the pattern-connections into its outer, working, position in order that through engagement with butts of the sinkers it may move the same radially outward. An improvement in the actuation of the sinkers during the production of split-work consists in actuating at this feed only the sinkers which cooperate with the instep needles. To this end, I employ sinkers having butts of two different lengths, as shown in Figs. 8 and 9, and at that side of the sinker-cam-ring G which is adjacent the auxiliary feed I employ a movable sinker-projecting cam, G², shown in Figs. 10 and 10^a, which is adapted to engage with the long butts only. The sinkers, 44, which are combined with the instep needles have long operating butts 44^a for engagement by the outthrow portion G⁴ of the said cam. The sinkers, 45, which are provided for cooperation with the heel and toe needles have short butts, 45^a, adapted to pass under the said outthrow portion G⁴ of the cam G², which is at a higher level than the guard portion G³ thereof. In consequence of this difference in level, the said cam has the stepped formation that is shown in cross-section in Fig. 10^a. Through the pattern-connections by which the radial position of cam G² is controlled, it is caused to occupy during round and round knitting an inward position in which its outthrow portion G⁴ does not engage with any of the sinker-butts. Consequently, during round and round knitting, in which the knitting proceeds at the main feed only, the sinkers pass the place of the auxiliary feed without having any radial movement communicated thereto. During heel and toe knitting such is the fact also. During split-work knitting how- 130

ever; at which time the auxiliary cams are in action and knitting proceeds in connection with the auxiliary feed as well as with the main feed, the cam G^2 occupies its working position shown in Fig. 10, and its out-throw portion G^4 engages with the upper portions of the long butts 44^a of the sinkers 44 of the instep needles, so that in passing the said cam the said sinkers are moved outward radially. As indicated already, the other sinkers are not actuated in passing the auxiliary feed, and remain in their inward positions between the needles. After passing the cam G^2 in either direction of movement of the needle-cylinder and sinker-ring in the reciprocating movement during split-work knitting, the sinkers which were radially projected by the outthrow portion G^4 of such cams are moved inward again by the appropriate retracting cam G^5 of the sinker-cam ring G , as usual.

The pattern-connections by means of which the position of cam G^2 radially is controlled, and the said cam is moved outward and inward at the required times in the working of the machine, comprise an arm 46 projecting outward from such cam and having in its outer portion a segmental slot 47 receiving the upturned inner end of a bar 48 carried by the upper arm of the lever 50. Consequently, as auxiliary cam-block B' is moved inward to place the auxiliary cams in working relations with the needles, the movement of the said lever which is instrumental in permitting auxiliary yarn-guide d^x to assume its working relations with the needles, as shown in the drawings, also operates through the engagement of bar 48 with the slotted arm 47 to draw cam G^2 radially outward into its working position shown in Fig. 10. So, also, when cam-block B' is moved outward to withdraw the auxiliary cams from working relations with the needles, the corresponding movement of the lever 50 and bar 48 operates to move cam G^2 radially inward to its inoperative position. Slot 47 in arm 46 is elongated and segmental to permit lateral play of said arm relative to the upturned inner end of bar 48 as the sinker-cam ring G plays to and fro horizontally, as usual, in the reciprocating action of the needle-cylinder and sinker-bed n^6 . Since the inward and outward movement of the portion of lever 50 which carries bar 48 is greater than the required extent of movement of cam G^2 radially, lost motion is provided for by mounting the said bar in a holder 49 upon the lever with capacity for endwise movement therethrough, the extent of the relative movement between the bar and the holder being defined by means of collars 52, 52, which are clamped by means of screws 53, 53, upon the bar at opposite sides of the said holder. Such extent may be varied as required by adjust-

ment of the said collars to positions at different distances apart upon the bar.

When the lever 50 occupies the position in which it is shown in Figs. 1 and 3, with its laterally-bent upper end-portion outward far enough to permit yarn-guide d^x of the auxiliary feed to occupy its feeding position, the latch-ring C may be lifted and lowered again by the operator without interference of the lower portion of the yarn-guide with said laterally-bent upper end-portion in the descent of the latch-ring. When the lever occupies its inward position, with the said laterally-bent upper end-portion acting to hold the said yarn-guide pressed inward and upward into non-feeding position, a lifting of the latch-ring by the operator will elevate the yarn-guide above and clear of the lever-end, so that the yarn-guide will swing outward above the lever-end, and when the latch-ring is lowered the knee-portion of the yarn-guide will encounter the top of the lever-end. To provide for this encounter the said knee-portion is formed with a bevel or incline d^3 , so that the yarn-guide will slip inward past the lever-end and into the non-feeding position again.

In the case of the upper or main series of butts, the butts 3^a , Fig. 5, of the instep needles are longer radially than those, 4^a and 5^a , Figs. 6 and 7, of the remaining needles. This obviously is not for cooperation with the lower instep-cam i^3 because such cam is at the lower level in the machine and butts 3^b , Fig. 5, are provided in the lower series of butts for cooperation with such cam. The purpose is to provide for the complete inward return of cam-block D into working relations with the needle-cylinder and the needles after having been drawn outward, as in order to permit of leveling the needles for a transferring operation at the time of beginning a fresh stocking. When the said block is permitted to move inward again, it is arrested by face-contact of one or more of its cams with the outer ends of butts of the main series. As soon, however, as the first long butts come around to the top guard cam v^5 in the revolution of the needle-cylinder their radially-projecting outer end-portions enter the passageway below such guard-cam and follow the usual knitting path below guard-cam v^5 and also below side-cam v^4 , so that as soon as the last of the preceding short-butts passes clear of the face of the said side-cam v^4 the cam-block D , under the pressure of the expanding pressure-spring d^y completes its movement inward into normal working relations with the needle-cylinder, and needle-butts.

The guard-cam c^{10} attached to one arm projecting from the upper end of stand i^7 serves to prevent butts of the upper series 130

from hitting against the left-hand end of upper instep cam i^4 (which acts upon butts of the upper or main series for the purpose of depressing the needles from the elevated 5 level to the normal working level again) in the first portion of the forward movement of the needle-cylinder in going off the toe. The pattern-barrel movement being timed to take place while upraised needles are at the 10 rear of cam i^4 , and the auxiliary cam-block B' being pulled out after the butts have begun to pass over the front widening picker, some of the butts are left in a high position and would catch against said end 15 of cam i^4 if guard-cam c^{10} were not arranged properly to depress them sufficiently to prevent.

What is claimed as the invention is:—

1. A split-work knitting machine having, 20 in combination, a needle-cylinder, needles, main and auxiliary yarn-feeds, main knitting cams for round and round and also reciprocating knitting, narrowing and widening pickers cooperating with said main knitting 25 cams, means for supporting said cams and pickers at one level in the machine, upper and lower instep cams, and an auxiliary set of radially-movable knitting cams for reciprocating knitting only, permanently 30 located opposite the main knitting cams, and having the said auxiliary set of knitting cams located at an entirely different level from that of the main knitting cams.

2. A split-work knitting machine comprising, 35 a needle-cylinder, needles, main and auxiliary yarn-feeds, main knitting cams, narrowing and widening pickers cooperating with said main knitting cams, means for supporting said cams and pickers at one 40 level in the machine, upper and lower instep cams, and an auxiliary set of knitting cams for split-work knitting, and having combined with such parts means for supporting said auxiliary set of knitting cams at a different 45 level in the machine, and means for effecting relative vertical adjustment between the different sets of cams to control the relative tightness or looseness of mesh of the respective knitted strips with relation to 50 each other.

3. A split-work knitting machine comprising, 55 in combination, a needle-cylinder, needles, main and auxiliary yarn-feeds, main knitting cams, narrowing and widening pickers 60 cooperating with said main knitting cams, means for supporting said cams and pickers at one level in the machine, an auxiliary set of knitting cams for split-work knitting, means for supporting said auxiliary set at a different level in the machine, and means for effecting relative vertical adjustment between the respective supports to thereby control the relative tightness or 65 looseness of mesh of the respective knitted strips with respect to each other.

4. A split-work knitting machine comprising, 70 in combination, a needle-cylinder, needles, main and auxiliary yarn-feeds, main knitting cams, narrowing and widening pickers 75 cooperating with said main knitting cams, means for supporting said cams and pickers at one level in the machine, an auxiliary set of knitting cams for split-work knitting, means for supporting said auxiliary set at a different level in the machine, and means for effecting vertical shift of the different sets of cams bodily in unison to vary the length of the stitches, and having combined with the said parts means for effecting relative vertical adjustment between 80 the said sets of knitting cams to control the relative tightness or looseness of mesh of the respective knitted strips with relation to each other.

5. A split-work knitting machine comprising, 85 in combination, a needle-cylinder, needles, main and auxiliary yarn-feeds, main knitting cams, narrowing and widening pickers 90 cooperating with said main knitting cams, means for supporting said cams and pickers at one level in the machine, an auxiliary set of knitting cams for split-work knitting, means for supporting said auxiliary set at a different level in the machine, and means for effecting vertical shift of the two supports 95 in unison to vary the length of the stitches, and having combined with the said parts means for effecting relative vertical adjustment between the respective supports to thereby control the relative tightness or 100 looseness of mesh of the respective knitted strips with respect to each other.

6. A split-work knitting machine comprising, 105 in combination, a needle-cylinder, needles including seam or suture needles, main and auxiliary yarn-feeds, main knitting cams, narrowing and widening pickers 110 cooperating with said main knitting cams, means for supporting said cams and pickers at one level in the machine, an auxiliary set of knitting cams for split-work knitting, 115 pickers for controlling said seam or suture needles for the production of seams or sutures, means for supporting the auxiliary set of knitting cams and seam or suture pickers at a different level in the machine, and upper and lower instep cams.

7. A split-work knitting machine comprising, 120 in combination, a needle-cylinder, needles including seam or suture needles, a main and auxiliary yarn-feeds, main knitting cams, narrowing and widening pickers 125 cooperating with said main knitting cams, means for supporting said cams and pickers at one level in the machine, an auxiliary set of knitting cams for split-work knitting, pickers for controlling said seam or suture needles for the production of seams or sutures, means for supporting the auxiliary set 130 of knitting cams and seam or suture pickers

at a different level in the machine, means for effecting relative vertical adjustment between the respective supports to thereby control the relative tightness or looseness of 5 mesh of the respective strips with respect to each other, and upper and lower instep cams.

8. A split-work knitting machine comprising, in combination, a needle-cylinder, needles including seam or suture needles, main 10 and auxiliary yarn-feeds, main knitting cams, narrowing and widening pickers cooperating with said main knitting cams, means for supporting said cams and pickers at one level in the machine, an auxiliary set 15 of knitting cams for split-work knitting, pickers for controlling said seam or suture needles for the production of seams or sutures, means for supporting said auxiliary set of knitting cams and said seam or suture 20 pickers at a different level in the machine, means for effecting vertical shift of the different supports in unison to vary the length of the stitches, means for effecting relative vertical adjustment between the respective 25 supports to thereby control the relative tightness or looseness of mesh of the respective strips with respect to each other, and upper and lower instep cams.

9. A split-work knitting machine comprising main and auxiliary yarn-feeds, a needle-cylinder, main knitting cams and narrowing and widening pickers at one level in the machine, upper and lower instep cams, auxiliary knitting cams at a different level for 30 split-work knitting, and needles having one complete series of butts at the level first-mentioned for cooperation with the main knitting cams, and a secondary series on the needles of one strip adapted for cooperation 35 with said auxiliary cams and with the lower instep cam.

10. A split-work knitting machine comprising main and auxiliary yarn-feeds, a needle-cylinder, main knitting cams and narrowing and widening pickers at one level in the machine, upper and lower instep cams, auxiliary knitting cams at a different level for split-work knitting, and needles having one complete series of butts at the level first 40 mentioned for cooperation with the main knitting cams, and a secondary series on the needles of one strip adapted for cooperation with said auxiliary cams and with the lower instep cam, said complete series of butts comprising one set of one length on needles 45 which are not actuated by the auxiliary cams and a set of a second length on the needles which are actuated by such cams.

11. A split-work knitting machine comprising, in combination, main and auxiliary yarn-feeds, a needle-cylinder, main knitting cams and narrowing and widening pickers at one level in the machine, upper and lower instep cams, auxiliary knitting cams and 50 seam or suture pickers at a different level for

split-work knitting, and needles having one complete series of butts for cooperation with the main knitting cams and a secondary series on the needles of one strip adapted for cooperation with said auxiliary cams and 55 with the lower instep cam, the needle-series including seam or suture needles having secondary butts for engagement with said seam or suture pickers.

12. A split-work knitting machine comprising main and auxiliary yarn-feeds, a needle-cylinder, main knitting cams and narrowing and widening pickers at one level in the machine, upper and lower instep cams, auxiliary knitting cams and seam or 60 suture pickers at a different level for split-work knitting, and a series of needles including seam or suture needles, said series of needles having one complete series of butts at the level of the main knitting cams 65 for cooperation with the latter and a secondary series of butts on the needles of one strip adapted for cooperation with said auxiliary cams and with the lower instep cam, said complete series of butts comprising one 70 set of one length on needles which are not actuated by the auxiliary cams and a set of a second length on the needles which are actuated by such cams.

13. A split-work knitting machine comprising, in combination, a needle-cylinder, a series of needles, main knitting cams, an auxiliary cam-block provided with an auxiliary set of cams for use in knitting split-work, widening pickers, a second radially-movable block carrying said widening pickers, and pattern-connections for automatically moving said widening-picker-block and said auxiliary cam-block radially to place said widening-pickers and auxiliary 100 cams in and out of operative relations with the needles.

14. A split-work knitting machine comprising, in combination, a needle-cylinder, a series of needles, main knitting cams, widening pickers, a radially-movable block carrying said pickers, and pattern-connections for automatically moving said picker-block radially to place said pickers in and out of operative relations with the needles. 110

15. A split-work knitting machine comprising, in combination, a needle-cylinder, a series of needles, main knitting cams, widening pickers, a radially-movable block carrying said pickers, means carried by said block for adjustably determining the waiting position of the widening pickers, and pattern-connections for automatically moving said picker-block radially to place said pickers in and out of operative relations 115 with the needles.

16. A split-work knitting machine comprising, in combination, a needle-cylinder, a series of needles, main knitting cams, widening pickers, a radially-movable block 120

- carrying said pickers, a tapering gauge-block adjustably mounted on said block for determining the waiting position of the widening pickers, and pattern-connections 5 for automatically moving said picker-block radially to place said pickers in and out of operative relations with the needles.
17. In a split-work knitting machine, the combination with a needle-cylinder, needles 10 including seam or suture needles, main knitting cams and widening pickers at one level, of a radially-movable auxiliary cam-block at a different level in the machine from that of the main knitting cams and widening 15 pickers, auxiliary cams for use in knitting split-work and seam or suture pickers carried by said auxiliary cam-block at the latter level, and adjustment-screws for said seam or suture pickers carried by said auxiliary cam-block.
18. In a knitting machine, in combination, the needle-cylinder, upper and lower cam-supports H and 2, main and auxiliary cam-systems carried by the said cam-supports, a pattern-controlled bar, as g^3 , connected with said support H, a holder connected with said bar g^3 , a depending bar, as 10, connected with said support 2 and entered into said holder, and means for 20 varying the height of said bar and the support 2 with relation to said holder and the support H.
19. In a knitting machine, in combination, the needle-cylinder, upper and lower cam-supports H and 2, pattern-controlled bars g^3 and 10 respectively connected with the respective cam-supports and also with each other, a bed-plate having a recess which is occupied by said bar 10, and means for 25 adjustably taking up side-play between bar 10 and the walls of said recess.
20. In a knitting machine, in combination, the needle-cylinder, upper and lower cam-supports H and 2, pattern-controlled bars g^3 and 10 respectively connected with the respective cam-supports and with each other, a bed-plate having a recess which is occupied by the bar 10, and adjustable 30 wedges at opposite sides of bar 10 for taking up play between the latter and the walls of the recess.
21. A knitting machine comprising, in combination, a needle-cylinder, needles, a main cam-block carrying narrowing pickers 35 and a block carrying widening pickers, said blocks radially movable with relation to the needle-cylinder, and adjustable stops for the respective blocks limiting the inward movement of the same toward the surface of the 40 needle-cylinder.
22. A knitting machine comprising, in combination, a needle-cylinder, upper and lower cam-blocks radially-movable and spring-actuated toward the surface of the 45 needle-cylinder, and a stop for preventing pressure of the cams of the upper cam-block against the said surface.
23. A knitting machine comprising, in combination, a needle-cylinder, a radially-movable picker-block spring-actuated toward the surface of the needle-cylinder, and an adjustable stop for limiting the approach of said block and its pickers to said surface.
24. The combination with the auxiliary cam-block, pattern-connections for controlling the position thereof, the auxiliary yarn-guide, and the movable sinker-cam adjacent said cam-block, of means intermediate said cam-block and the said sinker-cam and movable yarn-guide whereby as the cam-block goes into working position the sinker-cam and yarn-guide are caused to assume working positions, and when the cam-block is moved to non-working position the sinker-cam and yarn-guide are likewise moved to 50 non-working positions.
25. The combination with the auxiliary cam-block, pattern-connections for controlling the position thereof, the auxiliary yarn-guide, and the movable sinker-cam adjacent 55 said cam-block, of a lever intermediate said cam-block and the said sinker-cam and yarn-guide whereby all three simultaneously assume working positions or non-working positions, as the case may be.
26. In a knitting machine having main and auxiliary feeds, the combination with a sinker-cam ring having sinker-actuating cams corresponding with said feeds, at least one of the latter movable into working and 60 non-working positions respectively, of sinkers comprising a set having butts adapted to pass said movable sinker-cam without being engaged thereby, and a set having butts adapted to be engaged and actuated by the 65 said cam when in working position, and pattern-connections for controlling the position of the said movable cam.
27. In a knitting machine for split-work and the like, having main and auxiliary feeds, the combination with a sinker-cam ring having opposite sinker-actuating cams, that for the auxiliary feed of stepped formation and movable into working and non-working positions, respectively, of sinkers 70 comprising a set cooperating with the instep needles and having long butts, and a set cooperating with the other needles, and having short butts, and pattern-connections for controlling the position of the said movable cam.
- In testimony whereof I affix my signature in presence of two witnesses.
